(57) **CLAIM**

The ornamental design for a breast pump manifold, as shown and described.

DESCRIPTION

FIG. 1 is a rear perspective view of a breast pump manifold showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dash broken lines in the drawings depict portions of the breast pump manifold that form no part of the claimed design. The dash-dot broken lines define the boundary of the claimed design and form no part thereof.
